UNITED STATES PATENT OFFICE.

BARNET NEWLAND, OF NEW YORK, N. Y.

DESIGN FOR A FINIAL FOR LIGHTING-FIXTURES.

56,454.

Specification for Design.

Patented Oct. 26, 1920.

Application filed June 1, 1920. Serial No. 385,822. Term of patent 7 years.

To all whom it may concern:

Be it known that I, BARNET NEWLAND, a citizen of the United States, and a resident of the city of New York, in the county of New York and State of New York, have invented a new, original, and ornamental Design for Finials for Lighting-Fixtures, of which the following is a specification, reference being had to the accompanying drawings, forming part thereof.

The figure of the drawing shows the design of the article.

The figure is a plan view of finials embodying my design.

I claim:

The ornamental design for a finial for lighting fixtures, as shown.

BARNET NEWLAND.
